UNITED STATES PATENT OFFICE

2,639,452

SHOE POLISHING DEVICE

Porter D. Douglass, Oakland, Calif., assignor to
 Douglass Automatic Shoe Shining Co., a corporation of California

Application February 11, 1947, Serial No. 727,761

1 Claim. (Cl. 15—97)

1

This invention relates to shoe-shining machines, the primary object of the invention being to provide a machine in the form of a cabinet and which is coin-controlled, whereby a person may by inserting his foot and shoe into the cabinet, set certain machinery in motion, to shine or polish the shoe.

An important object of the invention is to provide reciprocating polishing members, which are so mounted that they will automatically adjust themselves to the shape of the shoe being polished or shined, to the end that the shining or polishing members will operate to shine or polish shoes of various shapes and sizes.

With the foregoing and other objects in view which will appear as the description proceeds, the invention consists of certain novel details of construction and combinations of parts, herein-after more fully described and pointed out in the claim, it being understood that changes may be made in the construction and arrangement of parts without departing from the spirit of the invention as claimed.

Referring to the drawings:

Figure 1 is a plan view of a shoe-shining cabinet constructed in accordance with the invention, a portion of the cabinet being broken away to illustrate the shining or polishing mechanism supported within the cabinet.

Figure 2 is a vertical sectional view through the cabinet, taken on line 2—2 of Fig. 1.

Figure 3 is an enlarged fragmental sectional view through the cabinet illustrating the forward ends of the polishing members.

Figure 4 is a plan view of the polishing or shining elements.

Figure 5 is an elevational view illustrating the polishing or shining members.

Figure 6 is a sectional view taken on line 6—6 of Figure 4.

Referring to the drawings in detail, the reference characters 5 indicates the cabinet of the machine, which includes a base 6 that extends an appreciable distance forwardly from the front of the machine, the front wall of the cabinet having the indentation 5' formed therein which is wide at its lower end providing clearance for the positioning of a shoe on the base.

Mounted within the cabinet, is a platform 7 which is provided with tracks 8 on which the wheels 9 of the carriage 10 operate.

At the forward end of the carriage 10, is a bearing 11 in which the vertical pin 12 operates, the pin 12 providing a connection between the carriage 10 and pivoted polishing or shining heads

2

13 which embody housings in which the backing members 15' are held, against which the rubber blocks 13 engage and over which are secured the polishing or shining members 14 that are in the form of strips of lamb's wool for contact with the surface being polished by the machine.

These polishing or shining heads 13 are shaped so that they will engage the surface of the shoe being shined, the members 14 moving around the heel of the shoe.

Spring arms 15 connect with the pin 12 and are curved to fit around the outer surfaces of the polishing or shining heads 13, where they are held in position by means of the pins 16 that extend from the outer surface of the heads 13.

The free ends of the spring arms 15 are curved as a 17 so the curved ends 17 contacting to limit movement of the spring arms towards each other when the shoe polished by the polishing heads has 20 extend from outer surfaces of the heads 13.

Rising from the base 6 is the curved flange 6' which has an inwardly extended flange 7' providing a guard that overlies the upper edges of the shining heads 13. The flange 7' defines the 25 opening 8' directly over the shining members of the machine, into which the shoe to be polished is inserted when placing the shoe within the machine.

The reference character 18 indicates a pair of pivoted arms that are connected to the spring arms 15, the outer ends of the arms 18 being connected by means of the coiled spring 19 that acts to normally urge the arms 18 together.

The arms 18 connect with the rod 20 through the collar 20' that slides longitudinally of the rod 20, the rod 20 being secured within the bracket 21 that rises from the carriage 10, as clearly shown by Figure 2 of the drawings.

Mounted within the cabinet, is the electric motor 22 that carries on its shaft an eccentric 23 that in turn is connected with the carriage 10, through the medium of the link 24.

It might be further stated that the motor 22 is of the type which is controlled and operated by 45 means of a coin inserted in a suitable coin-control mechanism not shown, and which is of the conventional type commonly employed in automatic machines of this type.

The spring arms 15 are wide and are supplied with wheels 25, whereby the mechanism may move freely within the cabinet to accomplish the purpose of the invention.

The reference character 26 indicates a mirror which is secured to the upper surface of the cabinet to lend to the attractiveness of the machine.

From the foregoing, it is believed that the structure and operation of the shoe-shining machine forming the subject matter of this invention, will be clear, and that further description as to the operation of the device is unnecessary.

What is claimed is:

In a shoe polishing device, a cabinet comprising a base, and a front wall having a shoe opening extending forwardly therefrom, a platform mounted on the base, a reciprocating wheel supported carriage mounted within the cabinet, movable over said platform, a pin rising from the carriage adjacent to one end thereof, a pair of horizontally disposed elongated polishing heads, said polishing heads being curved throughout their lengths adapted to completely encircle a shoe positioned therebetween, substantially wide spring arms secured against the sides of the polishing heads, pivotally mounted on said pin and normally urging the polishing heads towards each other to contact a shoe disposed between the polishing heads, a bracket rising from the carriage, a pair of horizontal pivoted arms connected between said spring arms and bracket, a coiled spring connected between the ends of the horizontal pivoted arms connected to said spring arms

normally biasing the polishing heads into contact with a shoe positioned between the polishing heads, a motor mounted on the base, a link connecting the motor to the carriage whereby said carriage is reciprocated, and the polishing heads are moved over a shoe held between the polishing heads, and the polishing members secured to and conforming to the curved surfaces of the polishing heads.

PORTER D. DOUGLASS.
